Primary Examiner — Eric Goodman*Assistant Examiner* — Amy Wierenga(74) *Attorney, Agent, or Firm* — Foley & Lardner LLP(57) **CLAIM**

I claim the ornamental design for a sealing gland, as shown and described.

DESCRIPTION

FIG. 1 is a perspective view of the claimed design; FIG. 2 is a cross-sectional view of section 2-2 of FIG. 1 of the claimed design of FIG. 1; FIG. 3 is a front view of the claimed design of FIG. 1, the rear view, the right side view, and the left side view are identical to the front view; FIG. 4 is a top view of the claimed design of FIG. 1; and, FIG. 5 is a bottom view of the claimed design of FIG. 1. The broken lines depict portions of the sealing gland that form no part of the claim.
